UNITED STATES PATENT OFFICE

ARTHUR GALBRAITH THORNTON, OF EDINBURGH, SCOTLAND

BAG OR CARRIER

Application filed November 26, 1927, Serial No. 235,935, and in Great Britain March 5, 1927.

This invention relates to a bag or carrier for small articles, such for example as tennis balls and the like, but applicable also as a carrier for other small articles.

5 The object of the invention is to provide a bag or carrier, which is preferably made of netting, and which can be readily closed and opened without the provision of a fastener, and which can be easily carried from the wrist 10 or arm.

According to this invention, the bag consists of a network or netted fabric made of twine, cord or the like material, and the mouth of the bag is attached to a bangle or 15 ring, which is preferably of such a size that it can be conveniently slipped over the hand and hung over the wrist, and is attached in such a manner to the ring that the attachments can easily move round the ring, so as to 20 either distribute the attachments more or less evenly around the ring and thus distend the mouth of the bag, or cause the attachments to assemble close together, thereby closing the mouth of the bag. The mouth of the bag is 25 preferably formed by the meshes of the netting being looped over the bangle or ring.

The meshes or loops of the network or netted fabric at the mouth of the bag must be of such a size that the diameter of the ring 30 is slightly smaller than the length of cord necessary to form two loops or four sides of a mesh, or the opening of one mesh or loops may be large enough to allow any two adjacent attachments to be spread apart sufficiently for the ring to pass between them.

The accompanying drawing illustrates one embodiment of this invention by way of example. Fig. 1 shows a ball bag or carrier suspended by the wrist and Fig. 2 shows the 40 bag with the mouth distended.

As shown, the bag is made of netting 3, the meshes of the netting being looped over a bangle or ring 4 so that the loops 5 form the mouth of the bag. The ring 4 can be slipped 45 over the hand on to the wrist or arm for the purpose of conveniently carrying the bag. The dotted circles 6 represent balls contained in the net bag. The weight of the balls causes the meshes of the mouth of the net bag to 50 close and draw the loops 5 together to the low-

er part of the ring 4, thereby closing the mouth of the bag.

On removing the bangle or ring 4 from the wrist or arm, the loops 5 can be readily distributed more or less evenly around the bangle or ring so as to open the mouth of the bag and enable a ball to be withdrawn or inserted. 55

The bangle or ring 4 may be made of any suitable metal or material, such as celluloid, for example, which can be of any desired colour or colours. 60

Claim:

A bag or carrier comprising a ring and a receptacle constructed of netting, the meshes of the netting being looped over the ring to form the mouth of the receptacle, the loops or meshes at the mouth of the bag being such that any two adjacent loops can be spread apart to allow the ring to pass between them, 70 whereby the mouth of the bag can be distended by distributing said loops around the ring, and the bag closed by assembling said loops together. 75

The foregoing specification signed at Edinburgh, Scotland, this 31st day of October, 1927.

ARTHUR G. THORNTON.
